[57] CLAIM

The ornamental design for a soccer ball trophy, as shown and described.

DESCRIPTION

FIG. 1 is a front elevational view of a soccer ball trophy showing my new design;

FIG. 2 is a side elevational view thereof, all sides being substantially similar;

FIG. 3 is a rear elevational view thereof; and,

FIG. 4 is a front elevational view of a second embodiment of FIG. 1, the difference residing in the removal of the reflective surfaces in the panels surrounding the central pentagon.
